UNITED STATES PATENT OFFICE.

WALDEMAR KOPS, OF NEW YORK, N. Y., ASSIGNOR TO KOPS BROTHERS, OF NEW YORK, N. Y.

APPAREL GARMENT.

Application filed October 5, 1922. Serial No. 592,472.

To all whom it may concern:

Be it known that I, WALDEMAR KOPS, a citizen of the United States, residing in the borough of Manhattan, city, county, and 5 State of New York, have invented an Improvement in Apparel Garments, of which the following is a specification.

This invention relates to an apparel garment and more particularly to that type of 10 garment shown and described in my applications, Serial Nos. 491,103, filed August 10, 1921 and 554,521, filed April 18, 1922. This type of garment is one that is made to wear next to the body as a combined under vest, 15 corset and brassière, the garment performing the functions of all three of the garments named so that instead of wearing three garments in the use of my improved garment but one may be worn. This garment 20 is preferably made of relatively light weight material which is sufficiently yielding to permit the garment to perform its intended functions and sufficiently soft to prevent the garment from injuring the skin. 25 The material of which the garment is constructed is also preferably a washable material so that the garment may be laundered in the usual manner of laundering under garments. While this garment is adapted for 30 general use it is particularly serviceable as an under garment to be worn in athletic sports, dancing and other similar exercises where entire freedom of movement of all parts of the body is necessary or desirable 35 and which cannot be obtained in the use of stayed corset garments, as commonly constructed. Furthermore, and to this end, the garment is so constructed as to completely cover the body from substantially the bust 40 to the thighs and to support and confine the busts as well as to confine the hips, thighs and abdominal portions of the body of the wearer.

The garment made in accordance with the 45 present invention preferably comprises a bust member adapted to extend around the body to support and confine the busts, and a hip, thigh and abdominal member also adapted to extend around the body to confine the hip, thigh and abdominal portions thereof. The members of the garment are 50 preferably connected along a predetermined line extending from substantially one axillary portion of the bust member to the corresponding edge thereof and from approxi-

mately the central portion of the hip, thigh and abdominal member to the corresponding axillary portion thereof, this line of connection extending along a portion of the lower edge of the bust member and along a portion of the upper edge of the hip, thigh and abdominal member. The construction is such, therefore, that the bust member is adapted to extend around the body from the front to the back and to be adjustably connected at the back, whereas the hip, thigh and abdominal member extends around the body from the back to the front and is adapted to be adjustably connected at the front, with the front upper edge of the hip, 60 thigh and abdominal member overlying a portion of the lower edge of the bust member so that the garment completely covers the body from substantially the busts to the thighs, as will be hereinafter more particularly described. 65

In the drawing:

Fig. 1 is a perspective view of the garment made in accordance with my invention.

Fig. 2 is a plan view of the parts of the 80 garment extended, and

Fig. 3 is an enlarged elevation showing the position of the parts of the garment in use.

Referring to the drawing, the garment 85 made in accordance with this invention comprises a bust member which may be constructed of a plurality of sections. As illustrated this bust member is formed of front sections 10 and 11, and back sections 12 and 13. The front sections are connected along a line of stitching indicated at 14, while the front section 10 is connected to the back section 12 along a line of stitching 15, and the front section 11 to the back section 13 along a line of stitching indicated at 16. 90 This member of the garment is adapted to extend around the body from the front to the back. At one edge the bust member is provided with a reinforced section 17 in which there is a series of eyelets 18, and at the opposite end with a corresponding reinforced section 19 in which there is a similar number of eyelets 20. At this edge of the 95 garment the same may be divided as indicated at 17' and one edge provided with a series of hooks 18' and the other edge with a corresponding series of eyes 19', in order, as hereinafter described to assist the wearer 105 in adjusting the garment to position on the 110

body. This member of the garment may also be provided with suitable shoulder straps indicated at 21 and 22, and the lower edges of the back sections may be inclined or tapered as indicated at 23 so as to extend upwardly from the edges of the member toward the front sections thereof, while the lower edge portion 24 of the front sections 10 and 11 extends appreciably below the adjacent portions of the back sections 12 and 13.

The hip, thigh, and abdominal member may also be made of a plurality of sections, and as illustrated this member consists of a back section 25, side sections 26 and 27 and front sections 28 and 29. The back section 25 is connected to the side section 26 along a line of stitching indicated at 30. The back section 25 is connected to the side section 27 along a line of stitching indicated at 31. The side section 26 is connected to the front section 28 along a line of stitching indicated at 32. The side section 27 is connected to the front section 29 along a line of stitching indicated at 33. As shown in the drawing this member may be provided with gore sections 34 and 35 placed in the lower portions thereof respectively between the side section 26 and the front section 28 and the side section 27 and the front section 29. At one edge the hip, thigh and abdominal member is provided with a reinforcement indicated at 36 and in which there is fitted a series of eyelets 37. Similarly the opposite edge of this member is reinforced as indicated at 38 and provided with a corresponding series of eyelets 39.

The hip, thigh and abdominal member may be provided with suitable hose supporters indicated at 40, 41 and which, as shown, are preferably attached to and depend from the gore sections 34 and 35. The hip, thigh and abdominal member is also connected to the bust member. As illustrated, this connection is made along the line of stitching indicated at 42 extending along a portion of the lower edge of the bust member from one axillar line thereof to the corresponding edge which, when the parts are attached, is substantially coincident with the upper central portion of the hip, thigh and abdominal member at the back thereof. This is clearly illustrated in Fig. 2 of the drawing.

In the use of the garment, as hereinbefore described the bust member is placed on the body and the parts adjustably connected to position by use of a lace 43 threaded through eyelets 18 and 20 either with or without first using the hooks 18' and the eyes 19' to assist in this adjustment. The hip, thigh and abdominal member is then passed around the body and the parts thereof adjusted to position by means of a lace 44 threaded through the eyelets 37 and 39, it being understood that the bust member passes around

the body from the front to the back, while the hip, thigh and abdominal member passes around the body from the back to the front. It will also be apparent that the upper portion of the hip, thigh and abdominal member at the front overlies the lower front portion of the bust member so as to cause the garment to completely cover the body from substantially the bust to the thighs.

I claim as my invention:

1. An apparel garment for use as a combined under vest, corset and brassière adapted to completely cover the body of the wearer from substantially the bust to the thighs comprising a bust member, and a hip, thigh and abdominal member, the said members being permanently connected along a line extending from one end of the bust member along the lower edge thereof to the axillar portion of the same and along the upper edge of the hip, thigh and abdominal member from the central portion thereof to the corresponding axillar portion, the lower edge at one end of the bust member being substantially coincident with the central portion of the upper edge of the hip, thigh and abdominal section, means for connecting the ends of the bust member at the back of the wearer, and means for connecting the ends of the hip, thigh and abdominal section at the front of the body of the wearer.

2. An apparel garment for use as a combined under vest, corset and brassière adapted to completely cover the body of the wearer from substantially the bust to the thighs comprising a bust member, a hip, thigh and abdominal member, the said members being permanently connected along a line extending from one end of the bust member along the lower edge thereof to the axillar portion of the same and along the upper edge of the hip, thigh and abdominal member from the central portion thereof to the corresponding axillar portion, the lower edge at one end of the bust member being substantially coincident with the central portion of the upper edge of the hip, thigh and abdominal section, the bust section being adapted to pass around the body from the front to the back and the hip, thigh and abdominal section being adapted to pass around the body from the back to the front with the line of connection between the sections of the garment overlying the body at approximately the waistline from the central back position to an axillar position, laces for connecting the ends of the bust section at the back of the wearer, and laces for connecting the ends of the hip, thigh and abdominal section at the front of the wearer.

3. An apparel garment for use as a combined under vest, corset and brassière adapted to completely cover the body of the wearer from substantially the bust to the thighs comprising a bust member, a hip,

thigh and abdominal member, the said members being permanently connected along a line extending from one end of the bust member along the lower edge thereof to the 5 axillary portion of the same and along the upper edge of the hip, thigh and abdominal member from the central portion thereof to the corresponding axillary portion, the lower edge at the end of the bust member being 10 substantially coincident with the central portion of the upper edge of the hip, thigh and abdominal section, the bust section being adapted to pass around the body from the front to the back and the hip, thigh and 15 abdominal section being adapted to pass

around the body from the back to the front with the line of connection between the sections of the garment overlying the body at approximately the waistline from the central back position to an axillary position, a 20 detachable end member in the bust section, devices for connecting the detachable end member to the adjacent edge of the bust member, laces for connecting the ends of the bust section at the back of the wearer, and 25 laces for connecting the ends of the hip, thigh and abdominal section at the front of the wearer.

Signed by me this 19th day of Sept., 1922.

WALDEMAR KOPS.
